GUARD FOR PUNCH PRESSES

Filed Dec. 22, 1919

UNITED STATES PATENT OFFICE.

ERIC ISCHINGER, OF ROCHESTER, NEW YORK, ASSIGNOR OF ONE-HALF TO FRANK KEIPER, OF ROCHESTER, NEW YORK.

GUARD FOR PUNCH PRESSES.

Application filed December 22, 1919. Serial No. 346,621.

The object of this invention is to provide a new and improved form of guard for punch presses.

This and other objects of the invention will be illustrated in the drawings, described in the specification and pointed out in the claims at the end thereof.

In the drawings,

Figure 1 is a front elevation of the punch press.

Figure 2 is a detail view of the swinging bridge in blank form, with the pivot head and a shock absorber mounted thereon.

Figure 3 shows a modified form of the connection between the press and the inner guard.

Figure 3^A is a detail view of an adjustable connection shown in Figure 3.

Figure 4 is a horizontal section on the line 4^x—4^x of Figure 5.

Figure 5 is a side elevation of the right hand side of Figure 4.

Figure 6 is a vertical section on the line 6^x—6^x of Figure 3.

Figure 7 is a detail view of the lower end of the locking pin and pad lock for locking the guard in place on the press.

Figure 8 shows a modified form of a locking device for preventing the tripping of the press while the bridge is open.

Figure 9 is a perspective view of the rear end of the bracket showing the adjustment of the guard.

In the drawings, like reference numerals indicate like parts.

In the drawings, reference numeral 1 indicates the punch press having the uprights 2 and 3 thereon, between which the ram of the press slides. On the upright 2 I fasten the hinge bracket 4 and on the upright 3 I fasten the lock bracket 5. On the hinge bracket is mounted to swing a hinge member or leaf 6. To this leaf is riveted or bolted a bridge 7 which is preferably made of cold rolled steel. The lock bracket 5 is recessed to receive the free end of the bridge and the bridge is made preferably longer than is needed to extend across the press between the brackets and is also made wider than the recess of the lock bracket. The hinge and bridge and lock bracket are fitted to the press and the bridge is then marked to locate

the opening of the lock bracket and is then cut away so as to make a close fit with this recess.

Presses are made in a great variety of sizes and by making the bridge and its sustaining parts in this way one size of bridge and parts can be accommodated to presses of considerable variation in size.

On the bridge is mounted to slide a yoke or pivot head 8 which makes a close fit with the bridge. The yoke or head is provided with the set screws 9 and 10 by which it may be clamped in any desired position on the bridge, the set screw bearing directly on the top of the bridge. As a substitute therefor, the opening in the yoke may be made sufficiently wide to contain the wedge 11 and the wedge 12. The wedge 12 may be forced down between the wedge 11 and the bridge 7 by the set screw 13 securely clamping the yoke 8 in place on the bridge. The yoke may also be perforated as indicated at 13^A and the bridge is perforated in like manner at frequent intervals so that a pin may be passed thru the yoke and the bridge locking the yoke in any position desired.

On the bottom of the yoke or pivot head is provided a boss 14 on which is carried a stud 15, on the outer end of which is mounted to rock a guard head 16 and on the inner end of which is mounted to rock the guard head 17 from which are supported the guard arms 18 and 19 and in which guard heads are adjustably mounted the guard arms. The inner guard head is slotted as shown at 20 and in this engages a pin or anti-friction roller 21 carried on a plate 22 adjustably mounted on the ram of the press so that as the ram moves up and down, the pin causes the inner guard head and guard arm 19 to rock therewith.

The hinge and lock brackets are first fastened to the frame of the press at the desired height and the bridge is then fitted to the lock bracket. Then the yoke is fastened in place to the bridge in front of the middle of the ram.

On the outer guard head 16 is connected the link 23. This link is connected on the right to the bell crank 24 pivoted at 25 on the lock bracket. This link is measured and fitted after all the other parts are in proper

place on the press. The upper end of the bell crank lever has connected thereto a link 25^a which in turn is connected to the actuating lever 26 pivoted at 27 on the side of the frame of the press. This actuating lever is connected by the link 28 and clamp 29 to the rod 30 that connects the treadle with the clutch of the press. A spring 31 is compressed between the clamp 29 and the lug 32 by which the parts are held in normal position. The actuating lever has a series of holes therein by which it may be adjustably connected to the press and the link 28 to fit presses of different sizes and conditions.

On the bridge 7 is carried a bracket 33 which may be clamped in position thereon by a set screw 34. On the bottom of this bracket is provided a boss 35 from which depends an arm 36 which carries a guard 37. A lug 38 is provided on the bracket and a lug 39 is carried on the guard arm which engages therewith and prevents the guard from swinging to the left but permits it to swing to the right and away from the ram of the press. The guard 37 prevents the operator from reaching around the guards 18 and 19 so that the operator is compelled to feed the press from in front of the press where the guards 18 and 19 will more effectively move his hand out of the danger zone.

The lock bracket 5 is perforated to receive a pin 40, which pin is adapted to pass thru the lock bracket on the outside of the bridge so as to securely lock the bridge to the bracket. This pin extends below the bracket and is perforated as indicated at 41 so that the hasp of a pad lock can be passed thru the pin to lock the bridge and guards thereon in place on the press. On the lock bracket is provided an eccentric lever 43 which is adapted to bear against the inner face of the bridge in order to force it against the pin to secure a firm engagement therewith and with the lock bracket. By withdrawing the pin 40 and disconnecting the link 23 from the bell crank 24 the bridge is released at the right so that it may be swung on the hinge to the left carrying the bridge and three guards away from the press.

On the lock bracket is mounted to slide a bolt 44, which bolt has a finger 45 thereon adapted when the bolt is moved to the left to engage under the upper arm of the bell crank 24 and lock the bell crank against rotation. This, in turn, will lock the press against being tripped. The bolt is normally pressed forward to the left by the spring 46, one end of which presses against a lug 47 on the bolt and the other end presses against the lug 48 on the bracket. The lug 47 extends up far enough so as to engage with the bridge and when the bridge is closed, the bracket is pushed back from under the upper arm of the bell crank, leaving the bell

crank 24 free to swing. When the bridge is open, the bolt is released and the spring pushes it forward into engagement with the bell crank, thereby locking the press against being tripped while the tools or dies on the press are being changed, it being understood that the bridge is unlocked and thrown around to the left when the tools are being changed and is thrown around to the right and locked in position while the press is being operated so as to secure the operation of both guards for the protection of the pressman.

In Figure 8 I have shown a modified form of this locking device, in which 50 represents the lock bracket and 7 indicates the bridge. On the right hand end of the bridge is fastened the clamp 51 having the tongue 52 thereon which extends rearwardly. On the lock bracket are mounted the lugs 53 and 54 between which is pivotally mounted the latch 55 having a shoulder or hook 56 on the lower end thereof. The latch extends upwardly at 58 and a spring 57 is provided between the extension and lock bracket normally holding the latch to the right at the top and to the left at the bottom with the hook in engagement with the actuating lever 26 holding it up and preventing the tripping of the press. When the bridge is closed, the tongue 52 engages the extension 58 and rocks it to the left compressing the spring 57 and removing the hook 56 from below the actuating lever 26. This will release the actuating lever and permit the operation of the press when the bridge is closed but will hold the actuating lever locked when the bridge is opened for the changing of the dies.

In Figure 3 I have shown a modified connection between the pitman and the inner guard. This consists of a link 60 having a turn buckle joint 61 therein and a ratchet face joint 62 therein. The lower end of the link connects to the crank 63 on the guard head by a ball and socket joint 64 and the upper end connects to the pitman by a ball and socket joint 65. When the bridge is opened, the bolt 66 is removed from the ratchet face joint permitting the freedom of movement of the bridge and when the bridge is closed these two parts of the ratchet face joint are clamped together by the bolt. The length of the link is adjusted by the turn buckle which moves the guard head and brings the guard into the correct normal position.

Instead of swinging the bridge to move the guards away from the front of the ram of the press, the pivot head may be loosened on the bridge to permit its sliding endways on the bridge either to the right or to the left of the ram of the press carrying the guards with it. For this purpose, only the link 23 must be disconnected from the bell

crank 24, and in this way the guards are placed at the side so as not to interfere with the setting of new dies.

In Figure 2, I have shown a shock absorber which consists of a sleeve of metal 70 loosely fitting on the bridge and attached to the pivot head 8. The guard head 16 carries an arm 71 that strikes the sleeve and raises it on the bridge, taking up the shock of the outer guard and preventing it from rebounding far enough to trip the press.

In Figure 9 I have shown the bracket 33 with an adjusting screw therein which may be turned to vary the normal position of the guard from the vertical.

It will be understood that there are three guards used in my invention. The outer guard driven by the treadle is named safety first, the inner guard driven by the ram is named safety second and the guard 37 is named safety third.

I claim:

1. A guard for punch presses having a bridge consisting of a bar, a head mounted to slide laterally on said bar, said bar and head having engaging surfaces adapted to prevent relative rotation, said head having an opening therethru to receive the bar, a boss on one side of said head having a stud 30 therein, a guard mounted to rock on said stud.

2. A guard for punch presses having a bridge consisting of a bar, a head mounted to slide on said bar, said bar and head having 35 engaging surfaces adapted to prevent relative rotation, said head having an opening therethru to receive the bar, a boss on one side of said head having a stud therein, a guard mounted to rock on said stud, means for clamping said head in position on the bridge.

3. A guard for punch presses having a bridge, said bridge being provided with a hinge bearing at the end thereof and being left blank at the other end thereof, a hinge 45 bracket at one end of the bridge, a lock bracket at the other end of the bridge, a recess in said lock bracket adapted to receive the blank end of the bridge, a pin for closing the outer end of the recess and holding 50 the blank end of the bridge in the recess.

4. A guard for punch presses having a bridge, a pivot head mounted to slide laterally on said bridge, a shock absorber mounted to rest on said bridge and attached to said 55 pivot head.

5. A guard for punch presses having a bridge, a pivot head mounted to slide on said bridge, a shock absorber mounted to rest on said bridge and attached to said pivot 60 head, a bracket mounted to slide on said bridge, guards depending from said pivot head and said bracket, means for clamping said bracket and said pivot head in place on the bridge.

6. A guard for punch presses comprising

a bridge, a lock bracket for supporting one end thereof, a bell crank on said bracket, a bolt mounted to move on said bracket into locking engagement with said bell crank when the bridge is open, said bridge holding 70 the bolt out of engagement with the bell crank when the bridge is closed.

7. A guard for punch presses comprising a bridge, a lock bracket for supporting one end thereof, a bell crank on said bracket, a 75 bolt mounted to move on said bracket into locking engagement with said bell crank when the bridge is open, said bridge holding the bolt out of engagement with the bell crank when the bridge is closed, said bell 80 crank holding the trip in the clutch of the press inoperative while the bolt is in locking position.

8. A guard for punch presses having a bridge, a lock bracket at one end of said bridge, a recess in said bracket adapted to receive the free end of said bridge, a pin for closing the outer end of the recess, an eccentric on said bracket adapted to clamp the bridge against said pin. 85

9. A guard for punch presses having a bridge, a lock bracket at one end of said bridge, a recess in said bracket adapted to receive the free end of said bridge, said bridge being recessed on one edge to positively engage with said lock bracket. 95

10. A guard for punch presses having a bridge, a lock bracket at one end of said bridge, a recess in said bracket adapted to receive the free end of said bridge, a pin for closing the outer end of said recess, said pin extending below the bracket and having an opening therethru by which it may be locked on the bracket. 100

11. In a guard for punch presses operated by a treadle, the combination of a pair of brackets, a bridge supported between said brackets, a guard mounted to operate from said bridge, a bell crank mounted on one of said brackets, one end of said bell crank being connected to said treadle and the other end of said bell crank being connected to said guard, means carried on said bracket to prevent the movement of said bell crank. 115

12. In a guard for punch presses operated by a treadle, the combination of a pair of brackets, a bridge supported between said brackets, a guard mounted to operate from said bridge, a bell crank mounted on one of said brackets, a sliding bolt mounted on said same bracket and adapted to engage said bell crank to prevent its movement in one direction, said bell crank being connected to said guard. 120

13. A guard for punch presses, the combination of a bracket fastened to the frame of the punch press, a bell crank mounted on said bracket, a bolt mounted to slide on said bracket, said sliding bolt being adapted to engage said bell crank and prevent its move- 125

ment in one direction, a bridge member adapted to engage said bracket and move said sliding bolt out of engagement with said bell crank, means carried on said bracket to automatically move said bolt into engagement with said bell crank on the movement of said bridge member away from said bracket.

14. A guard for punch presses having a bridge, a pivot head mounted to slide on said bridge, a bracket mounted to slide on the bridge, guards depending from said pivot head and said bracket, means for clamping said bracket and said pivot head in place on the bridge.

15. A guard for punch presses having a bridge, a bracket mounted to slide on the bridge, a guard depending from said bracket and swinging in one direction only, means for clamping said bracket on the bridge.

16. A guard for punch presses having a bridge, a bracket mounted to slide on the bridge, a guard depending from said bracket and swinging in one direction only, means for clamping said bracket on the

bridge, means for angularly adjusting the normal position of the guard on the bracket.

17. A guard for punch presses comprising a hinge bracket and a lock bracket, a bridge supported between said brackets and hinged to said hinge bracket, a head adjustably clamped to said bridge, a guard mounted to swing on said head.

18. A guard for a punch press having a movable ram, a hinge bracket and a lock bracket mounted on the frame of the press, one on each side of said movable ram, a bridge supported between said brackets and hinged to said hinge bracket, a head adjustably mounted on said bridge, a cam pivotally mounted on said head, an operating member adjustably mounted on said movable ram, said head being adapted to be adjusted laterally on said bridge with relation to said operating member on said ram to change the angular motion of said cam when operated by said operating member, a guard carried by said cam.

In testimony whereof I affix my signature.

ERIC ISCHINGER.
